UNITED STATES PATENT OFFICE

2,418,058

CONVERTIBLE SHIRT COLLAR

Simon Touloumis, Troy, N. Y., assignor to Cluett
Peabody & Co., Inc., Troy, N. Y., a corporation
of New York

Application July 16, 1943, Serial No. 494,959

3 Claims. (Cl. 2—131)

1

This invention pertains to wearing apparel and more particularly to shirt collars of the convertible type, the object of the invention being to provide a convertible collar having means operative to establish distinct lines of fold about which the collar may be folded when worn turned up or turned down respectively.

In the accompanying drawings wherein one desirable embodiment of the invention is illustrated by way of example,

Fig. 1 is a fragmentary front elevation of a shirt having the improved collar of the present invention attached thereto, the collar being shown turned down as a sport collar;

Fig. 2 is a view similar to Fig. 1 but showing the collar turned up for use with a necktie;

Fig. 3 is a view of the rear ply of the collar;

Fig. 4 is a view similar to Fig. 3 but showing the inside of the rear ply, the collar being turned inside out;

Fig. 5 is a section to larger scale on the line 5—5 of Fig. 4;

Fig. 6 is a section to larger scale on the line 6—6 of Fig. 4; and

Fig. 7 is another section of the same, to larger scale, approximately midway between lines 5—5 and 6—6 of Fig. 4.

Referring to the drawings the numeral 1 designates a shirt of customary type having the attached collar 2. As illustrated in Fig. 1, the collar 2 is turned down for use as a sport collar, being folded along the line 4. In Fig. 2 the collar is turned up and folded along the line 5.

The front ply 6 of the collar (Figs. 5 and 6) is preferably a single unitary piece of material extending through the top portion and neck band portions of the collar. The collar has the interliner portion 7 which, as here illustrated, is also a single piece of material of substantially the same dimensions as the front ply 6.

The rear ply of the collar comprises the top portion 8 (Fig. 4) and the neck band portion 9, said parts being united by a seam 10, the junction of the parts 8 and 9 providing the edge 11 (Figs. 4 and 5) which forms the fold line about which the collar is folded when worn in the position of Fig. 2. The rear ply of the collar also comprises the auxiliary piece 12, preferably of somewhat stiffer material than the fabric which forms the neck band proper, and which is of less length than the outer ply of the neck band. The member 12 is symmetrically disposed with respect to the outer ply of the neck band and at its central portion is caught into the seam 10 which unites the parts 8 and 9. The part 12 tapers

2

in width at its opposite ends, thus providing the edges 13 (Fig. 4) which diverge downwardly and outwardly from the edge 11 as viewed in Fig. 4. Seams 14 unite these divergent edge portions of the part 12 to the body portion of the neck band. The edges 13 define secondary fold lines at opposite ends of the collar about which the collar may be folded when worn in the turned-down position of Fig. 1. Since there is but a single thickness of the relatively thin neck band material between the fold lines 11 and 13, the collar tends to fold about one of the lines 11 or 13, and the single piece front ply insures a smooth un wrinkled appearance where it extends across the single thickness of the rear ply between the lines 11 and 13. Thus whether the collar be worn turned up or turned down it folds smoothly and without tendency to wrinkle, thus providing a much neater appearance than it has heretofore been possible to obtain with previous constructions of convertible collars.

In the manufacture of a collar in accordance with this invention, the first step is to cut all of the pieces to shape and size. The pieces may then be connected together in the following sequence:

- (1) The neckband reinforcement 12 is disposed face to face with and stitched to the lower piece 9 of the rear ply;
- (2) The pieces 8 and 9 are superposed face to face, with the piece 12 on the outside and the lower strip or piece 9 is stitched to the upper part 8 of the rear ply along a line spaced substantially from an edge, such as the line of stitching 10a;
- (3) The piece 9 is then turned over along the line of stitching 10a, so as to extend away from piece 8, and the pieces 8 and 9 again stitched together along line 10.
- (4) The face ply 7 and the stiffener or interliner 6 are aligned and disposed face to face, then disposed against the rear ply with the stiffener 12 on the outside, as shown in Fig. 5, and the superposed plies stitched together by the stitching 10a;
- (5) The collar is next turned inside out, and then may be secured to a shirt.

While one desirable embodiment of the invention has herein been disclosed by way of example it is to be understood that the invention is broadly inclusive of any and all equivalent constructions whereby the same result is attained and which fall within the scope of the appended claims.

I claim:

1. A convertible shirt collar comprising a facing ply and a rear ply, the rear ply comprising

parts having divergent edges which define two distinct fold lines about which the collar may be folded whether worn turned up or turned down, respectively, and a single thickness of material bridging the space between said edges, the rear 10 ply being of single thickness between said fold lines.

2. A convertible shirt collar comprising a facing 15 ply and a rear ply, the rear ply of the collar comprising two overlapping parts of material united by a seam which extends along and closely adjacent to the edge of one of said overlapping parts, said edge forming one fold line, a second seam divergent from the first and which also unites two overlapping parts of material, said last mentioned seam extending along and closely adjacent to an edge of one of said last mentioned overlapping parts, said last named edge forming a second fold line, the rear ply being of single thickness between said fold forming edges.

3. A convertible shirt collar comprising a facing 20 ply and a rear ply, the rear ply comprising

5 top and neck band portions having overlapping margins united by a seam, the junction of said margins by said seam providing an edge which forms one fold line, the rear ply also comprising a stiffener member united to the neck band portion by a seam, said stiffener member having edge portions which diverge from the aforesaid fold forming edge and which define a second fold line, the rear ply being of single thickness intermediate said fold forming edges.
